UNITED STATES PATENT OFFICE.

HENRY JAMES HERINK, OF LONDON, ENGLAND, ASSIGNOR TO THE RELAY AUTOMATIC TELEPHONE COMPANY, LIMITED, OF LONDON, ENGLAND.

SEMI-AUTOMATIC TELEPHONE SYSTEM.

1,250,583.

Specification of Letters Patent. Patented Dec. 18, 1917.

Application filed March 9, 1917. Serial No. 153,626.

To all whom it may concern:

Be it known that I, HENRY JAMES HERINK, a subject of the King of Great Britain, and resident of Marconi House, Strand, London, 5 England, have invented a new and useful Improvement in Semi-Automatic Telephone Systems, of which the following is a specification.

This invention relates to semi-automatic 10 telephone systems in which there is a satellite exchange connected with a manual central exchange. This application claims more particularly the metering and associated arrangements, certain other features 15 being claimed under my application No. 130551.

The object of the invention is so to arrange the circuits and the apparatus at the satellite that while a calling subscriber can 20 clear until the operator has inserted her plug in answer to his call, so soon as she has done so the circuits are under her control so that she can actuate the subscriber's meter even after he has replaced his receiver, which she does by sending alternating current over the trunk to the satellite.

My invention is illustrated by the accompanying drawings of which:—

Figure 1 shows a circuit associated with 30 double pre-selector line finder relay switches as described in British Patent No. 102330. A subscriber's line has thereby access to a plurality of two-wire trunks to an A position at a manual exchange.

Fig. 2 shows my invention applied to a 35 relay system of the type described in British Patent No. 9840 of 1914 and United States Patent Serial No. 832471, with certain modifications.

Fig. 3 shows the use of repeaters in the 40 transmission circuits and other features.

At the satellite (Fig. 1) I employ two 45 supervisory relays S1R and S2R, two guarding relays G1R and GR, a supervisory switching relay SSR, a marginal change-over relay MCR and a metering relay SMR adapted to respond to alternating current, while at the A position on the manual 50 board I have a line relay L1R, a cut-off relay CO1R, a metering recording and metering switching relay MSR.

The operation of the circuit is as follows:—

The calling subscriber on lifting his receiver obtains connection with a trunk as

described in British Patent No. 102330. Circuits 0 and 1 are completed and cut-off relay COR energizes but SM does not. It is to be noted that both these circuits are over back contacts of GR. Circuit 2 is also 60 completed and S1R energizes, in turn energizing SSR in circuit 3. G1R is now energized by circuit 4, and adds to circuits 0 and 1 by paths 0^a and 1^a respectively over this relay. Circuit 5 is now complete, energizing L1R at the manual exchange but not MCR.

L1R completes circuit 6 and the calling lamp CL glows. Now if the calling subscriber clears before the operator answers, 70 S1R deenergizes, then SSR which opens circuit 4 of G1R before the latter deenergizes, GR energizes over circuit 6^a.

When G1R does release, the circuits 0 and 1 are opened during the time between 75 the falling off of G1R and GR. This time is sufficient to release the line finder.

Assuming that the calling subscriber does not clear before the operator answers, the insertion of the plug energizes CO1R over 80 circuit 6^b and cuts out L1R and circuit 6. MCR now energizes over circuit 7.

GR energizes over circuit 8 and maintains itself over circuit 9 which is established before circuit 7 is broken. Circuit 1 85 is now retained over G1R and MCR deenergizes by the opening of circuit 7 at GR.

S4R and S2R are energized via circuit 10. Lamp SL is shunted out by circuit 6^c. S2R energizing connects circuits 11 and 12 to 90 earth and thus controls GR and G1R.

Thus it is seen that the release of a line finder by retaining circuit 0 is controlled from S2R which is maintained over the answering plug circuit. When the operator inserts a plug, the control of the circuit thus passes from the calling subscriber to the operator. The calling subscriber is able, by moving the switch-hook and opening and closing circuit 2, to cause S1R and 100 SSR consecutively to energize and deenergize, thus diverting circuit 10 to 10^a via resistance R. This resistance is such that S4R will also deenergize and reenergize, but S2R is of such a resistance that it will continue to be maintained energized. Thus circuit 6^c is alternatively opened and closed to flash lamp SL.

The operator is now able to obtain the number required by the calling subscriber 110

and completes the connection in a well known manner. At the termination of conversation, the calling subscriber will open circuit 2 and cause SL to glow as previously described.

5 The call, if effective, will be metered. If ineffective, or on no-fee service, the operator will simply withdraw the plug. In any case the clearing of the circuit is unaffected by metering.

10 If the operator depresses meter key K, circuit 13 energizes MSR which by switching in its low resistance winding energizes the operator's meter in a well known manner.

15 MSR causes an alternating current, superimposed upon a continuous current, to pass over circuits 14 and 10^a. The continuous current maintains S2R but the alternating current energizes SMR which maintains itself over 15. Circuit 16 is now completed to short-circuit resistance RO and increase the current in the subscriber's meter so that it is energized. The operator now withdraws the plug. MSR, CO1R deenergize, then 25 S2R. The latter causes circuits 11 and 12 to be opened. G1R falls off first and then GR. The interval of time is sufficient to release the line finder as previously described.

30 Fig. 2 shows a subscriber's line equipment connected at CR1, CR2, in a relay system of the type described in British Patent No. 9840 of 1914 and United States Patent Serial No. 832471, extended to a transmission circuit according to a modification of my invention. According to Fig. 1, the operator can only cause the meter to register after the subscriber has replaced his receiver. The subscriber can therefore hold the trunk against the wishes of the operator. According to Fig. 2, the operator controls the trunk absolutely and can register a call whether the receiver is replaced or not. The trunk is shown plug-ended, and when this plug has been inserted into the jack of the wanted line the operator has full control, and when the plug is withdrawn after conversation the connection is released back to the line and cut-off relay independent of any action of the caller. It is to be understood that this 45 feature is applicable to the system of Fig. 1 or to any other system, and the transmission circuit of Fig. 1 has also such wide application.

50 The operation of Fig. 2 is as follows:—
55 The subscriber lifts the receiver and circuit 1 is completed to energize the line relay LR. The line is then connected to an idle trunk in the manner described in British Patent No. 9840 of 1914 and United States Patent Serial No. 832471. Relay SR energizes over circuit 2; relay SSR energizes over circuit 3; relay G1R energizes over circuit 4. Relay COR, energizing over circuit 5, cuts off LR and energizes relay AR 60 over circuit 18. Circuit 6 is completed by

SSR, and relay LR2 (but not relay MCR) energizes completing circuit 7 to glow lamp S3L. Let it be assumed that the subscriber now replaces his receiver. Circuit 2 is broken, and SR and SSR deenergize, causing circuits 4 and 6 to open, thus releasing the trunk. Assuming that the calling subscriber does not clear at this stage and the operator answers in a well known manner by operating key K¹, she obtains the number required. She then inserts the calling plug into the required line jack when relay SCR operates and lamp S4L glows in circuit 8. The subscriber may be rung manually or by automatic devices well known in the art.

70 The operation of SCR earths the "A" line of the trunk and causes MCR to operate over circuit 9. GR now energizes in circuit 10. S2R energizes in circuit 11 and G1R is maintained over circuit 12. GR is maintained over circuit 13 which is established before circuit 9 is broken. MMR energizes over circuit 13^a. The calling subscriber may flash the operator as described for Fig. 1 if he so desire. Relays SR and SSR energize 80 and deenergize and make and break circuit 11, so that S3R is deenergized and energized to cause lamp S3L to glow intermittently. The operator, assuming the call to have been effective, will depress K2 to energize the operator's meter SM3 and relay MSR over circuit 14. The latter relay causes SMR to energize by alternating current over circuit 15. SMR holds itself over circuit 16 and cuts out MMR but itself remains energized sufficiently 90 long, owing to the slow release of MMR, to complete circuit 17 to short-circuit the resistance in earth of circuit 5, and the increased current causes subscriber's meter SM to energize. The calling subscriber may or may 100 not have replaced his receiver.

95 In the latter case, the operator by withdrawing the calling plug causes SCR to deenergize, thus opening circuit 11 and causing S2R to deenergize. Circuit 12 being 110 opened, G1R deenergizes and opens circuit 5 to deenergize CR1 and CR2. GR also deenergizes, but being slow to release does not prevent the breaking down of the connection. COR deenergizes but relay AR (see 115 United States Patent Serial No. 101769) is maintained energized over circuit 18, thus giving the calling subscriber the busy-tone. (This facility can also be utilized when the wanted subscriber is busy, the operator then 120 momentarily putting the sleeve of the calling trunk plug to earth in any well known manner. This will give the calling subscriber busy-tone and release the trunk).

125 If the calling subscriber replaces the receiver before the withdrawal of the plug, the operator will meter as already described. Circuit 2 being open at the switch-hook, SR, SSR deenergize, then S3R because the short-circuit of resistance R in circuit 11 is re- 130

removed by SSR. Circuit 14^a being then completed, lamp S3L glows. When the called subscriber replaces his receiver, S4R deenergizing removes the shunt R4 so that lamp 5 S4L glows.

Fig. 3 shows my invention used with repeater coil transmission. This arrangement like the others may be used with any connecting scheme and any method of operating control. The figure actually shows an arrangement which has a jack-ended trunk and in which the operator cannot completely release the connection unless the calling party has replaced the receiver.

15 The operation of the circuit is as follows:

When the receiver is lifted to call, a subscriber's line is extended to a trunk in any known manner. Circuits 0 and 1, Figs. 1 20 and 2, are completed, the cut-off relay energized and the line relay disconnected, as before described.

Relay S5R is now energized over circuit 2, and circuit 3 being completed SSR energizes. Circuit 4 being completed G1R energizes and adds to circuits 0 and 1 by paths 25 0^a and 1^a respectively. Circuit 5 is also completed by SSR and L1R energizes but not MCR. L1R completes circuit 6 and 30 lamp SL glows.

If the caller clears at this stage, circuit 2 opens and causes S5R to deenergize. GR energizes over circuit 7 and holding itself over circuit 8 releases its connection as described 35 for Fig. 1.

When the operator answers before the subscriber clears, circuit 8^a, completed over the plug third conductor, energizes CO1R which cuts off relay L1R so that it deenergizes and lamp SL ceases to glow.

MCR is energized over circuit 9, as described for Fig. 1. This relay energizes GR over circuit 10 and the later retains over circuit 8 which is established before circuit 45 9 is broken. Circuit 11 is now established over the plug, as in Fig. 1; S2R energizes and switching in its low resistance winding, 11^a causes the supervisory relay of the operator's cord circuit to energize, as in Fig. 1. 50 The caller may now flash the operator as before described. S5R and SSR open and close the low winding of S2R. The caller replacing the receiver permanently glows the supervisory lamp in a similar manner. 55 The operator then depresses the meter key (Fig. 1) and energizes MSR over 8^b, causing SM1R to energize over circuit 14. The latter relay retains over circuit 14^a a relay MHR having been energized via circuit 13. 60 MHR being slow to release circuit 15 is established a sufficient time to short-circuit resistance RO, causing the meter of the calling subscriber's line to operate as in Fig. 2.

It is to be noted that G1R is retained ener-

gized over circuit 12, and that SSR is de- 65 energized by circuit 3 being open at S5R. Therefore when the operator withdraws the plug, S2R deenergizes and opens circuit 12 so that G1R is deenergized. The retaining 70 circuits 0 and 1 are opened between the deenergizations of G1R and GR, a sufficient length of time to release the connection.

What I claim is:

1. In a semi-automatic telephone system using two-wire trunks, the combination of a 75 subscriber's meter control relay adapted to respond to alternating current only and means whereby, after a calling line has been extended to an operator's connecting equipment, alternating current may be applied to 80 the control relay to effect registration.

2. In a semi-automatic telephone system using two-wire trunks, the combination of a 85 subscriber's meter control relay adapted to respond to alternating current only, means for enabling a caller to return all apparatus to normal before the operator replies, means for preventing him from doing so thereafter and means for enabling the operator when once the answering plug has been inserted 90 to apply alternating current to the control relay and to return apparatus to normal.

3. In a semi-automatic telephone system using two-wire trunks, the combination of a 95 meter control relay adapted to respond to alternating current only, a condenser, a double wound relay operatively connected across a trunk at a satellite exchange, means whereby the meter control relay and the condenser are connected in parallel with the double 100 wound relay, means for retaining the last mentioned relay energized by continuous current and a meter key adapted to energize the meter control relay by alternating current. 105

4. In a semi-automatic telephone system using two-wire trunks, the combination of a repeater, a condenser connected between two windings of the repeater, a relay shunting the condenser, a meter control relay and a 110 second condenser both connected in parallel with the first mentioned relay, means for energizing the first relay by continuous current and a meter key adapted to energize the meter control relay by alternating current. 115

5. In a semi-automatic telephone system using two-wire trunks, the combination of a 120 subscriber's line, a meter control relay associated therewith and adapted to respond to alternating current only, a relay operatively connected to the line and adapted to extend the line to a trunk, means actuated by the answering of an operator for cutting off the second relay from the line and means for applying alternating current to the meter 125 control relay.

6. In a semi-automatic telephone system using two-wire trunks, the combination of

a subscriber's line, a meter control relay associated therewith and adapted to respond to alternating current only, a marginal relay operatively connected to the line and adapted to extend the line to a trunk without itself operating, means actuated by the answering of an operator for operating the marginal relay and for cutting it off from the line and means for applying alternating current to 10 the meter control relay.

7. In a semi-automatic telephone system using two-wire trunks, the combination of a subscriber's line, a meter control relay associated therewith and adapted to respond 15 to alternating current only, a relay operatively connected to one line branch of the subscriber's line, means actuated by the answering of an operator for energizing the second relay over the line, means whereby 20 the operation of the second relay enables the operator to release and means for applying

alternating current to the meter control relay.

8. In a semi-automatic telephone system using two-wire trunks, the combination of a 25 subscriber's line, a meter control relay associated therewith and adapted to respond to alternating current only, two slow release relays adapted to control release, means whereby one of such relays is controlled 30 partly by the calling subscriber and partly by the operator, means whereby the other of such slow release relays is controlled by the answering of the operator, means for transferring release from the first to the second 35 of such relays and means for applying alternating current to the meter control relay.

In testimony that I claim the foregoing as my invention, I have signed my name this 14th day of February, 1917.

HENRY JAMES HERINK.
